CLAIM

The ornamental design for a dispenser for a sanitary appliance, as shown and described.

DESCRIPTION

FIG. 1 is a frontal perspective view thereof;
FIG. 2 is a frontal elevational view thereof;
FIG. 3 is a rear elevational view thereof;
FIG. 4 is a first side elevational view thereof;
FIG. 5 is a second side elevational view thereof;
FIG. 6 is a top plan view thereof; and,
FIG. 7 is a bottom plan view thereof.

The portions of the design depicted in broken lines form no part of the claimed invention.
